(57) **CLAIM**

The ornamental design for a pet feeder as shown and described.

DESCRIPTION

FIG. 1 is a front, right and top perspective view of a pet feeder showing my new design;

FIG. 2 is a rear, left, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is an enlarged view of encircled portion 9 of FIG. 1. The evenly-spaced broken lines depict portions of the pet feeder that form no part of the claimed design. The dot-dash-dot lines represent boundaries of the enlarged views and form no part of the claimed design.

1 Claim, 9 Drawing Sheets
